OIL FIELD DERRICK OR THE LIKE

Charles L. Fox, Oklahoma City, Okla.

Application August 13, 1940, Serial No. 352,461

6 Claims. (Cl. 189—16)

My invention relates to improvements in the construction of fabricated structural steel derricks especially, although not exclusively, adapted for use in drilling and operating oil wells and the like.

The primary object of my invention is to provide an improved arrangement and proportioning of leg sections, girts and diagonal braces whereby the safe load and wind load capacities are materially increased as well as greater resistance to loosening due to vibration caused by drilling and other operations.

Another important object of my invention is to provide a stronger, more rigid and more easily connected joint between related leg sections, characterized by intermediate braced leg columns at the same distance throughout the height of the legs, and by staggered leg section joints.

Other important objects and advantages of my invention will be apparent from a reading of the following description of the appended drawings, wherein for purposes of illustration a preferred embodiment of my invention is shown.

In the drawings—

Figure 1 is a general perspective view of the embodiment.

Figure 2 is a fragmentary elevational view of the rotary front of the derrick showing the starting legs comprising two sections and the two intermediate sections located immediately thereabove.

Figure 3 is a fragmentary elevational view of the ladder or forge side of the derrick showing the starting legs comprising two sections and the two intermediate sections located immediately thereabove.

Figure 4 is an enlarged perspective view showing a typical intermediate section.

Figure 5 is a side elevational view showing a group of typical intermediate sections.

Figure 6 is a side elevational view showing a group of typical top sections.

Figure 7 is an enlarged fragmentary horizontal sectional view taken through a corner of the derrick.

Referring in detail to the drawings, my improved derrick comprises four legs designated by the numeral 5. The first and second horizontal girts 6 and 7 extend across three sides of the derrick but are abbreviated on the fourth side as indicated by the numerals 6' and 7', so as to provide for the V-opening 8. All of the upwardly succeeding girts 9, 10, etc., extend across all four sides of the derrick and are vertically spaced at the same intervals as the first two girts 6 and 7.

at the distance required by present American Petroleum Institute specifications.

There are four diagonal braces 11, 12, 13 and 14, respectively, in each panel of the derrick. 5 These diagonal braces are connected by securing to upper and lower plates 15 and 16 to extend vertically above and below the middle points of the girts, with the outer ends of the braces secured to the legs 5 at points midway between 10 the adjacent girts, so as to form a reclining diamond form of bracing in each panel.

This method of applying the bracing greatly relieves the load heretofore thrown on the girts, reduces the unsupported length of the legs 5, 15 and eliminates the crossing of any brace over the other. In this way the braces are made stress carrying members and the amount of stress on any individual diagonal brace is only a fraction of the actual safe load capacity for 20 the size of brace used in accordance with American Petroleum Institute specifications.

Both the girts and the diagonal braces are formed of angle-iron fabricated steel and placed in position with their flanges laterally outwardly directed, thereby facilitating assembly and providing additional clearance in the interior of the derricks.

The legs 5, to which the girts and diagonal braces are attached, are made up of staggered sections. The starting or bottom leg sections are all of the same length and extend to the second girt 7, but the next leg sections consist of two full length sections and two half-length sections placed in diagonally opposite positions. 30 Thereabove all the leg sections are of full length until the top section which has two half-length leg sections and two full length leg sections are disposed in diagonal opposition. In a typical intermediate section of the derrick such as shown 35 in Figure 4 of the drawings the full length leg sections comprise a diagonally opposed pair 17 which extend below the lower girt with accompanying braces and a diagonally opposite pair 40 of leg sections 18 which extend above the upper girt with accompanying braces. The staggering of the leg joints accomplished in this way interrupts and disrupts the vibration frequency throughout the height of the derrick set up by 45 the operation of the drilling equipment thereby substantially eliminating loosening of joints and shearing of bolts and liability to structural failure at moments of overload. This, by construction in conjunction with described arrangement 50 of bracing, provides the greater resistance of the 55

derrick to twisting which is characteristic of the present invention.

In the top sections the braces 11', 12', 13' and 14' corresponding to the braces of the intermediate sections are necessarily foreshortened and arranged at a more acute angle as is evident from Figure 6 of the drawings.

The bolted leg joint construction employed in the present arrangement exhibits very exceptional superiority over present bolted joints in point of strength and in point of simplicity and ease of assembly. As shown in Figure 7 of the drawings, the joint consists of two angle iron plates 19 and 20, respectively, fitted on the inside of and the outside of the leg section 5, with bolts 21 and 22, respectively, being bolted through the respective flanges after the next leg member is placed between them. In this way a rigid joint is provided having a greater load capacity than the calculated capacity of the leg section itself. As indicated in the drawings the vertical flanges of the girts are bolted to the joints and bear directly against the outer angle-iron plates 20, thereby further adding strength and rigidity to the derrick as a whole.

On the rotary side the elements 23 and 24 which with the girt 9 define the rotary opening, extend from the lower ends of the legs 5 past the girt 9 to the connection plate 16 at the girt 10. In the panel bounded by the girts 9 and 10 there is, besides the diagonal braces 11, 12, 13, and 14, a perpendicular brace 25 connected at its upper end to the plate 16 and at its lower end to a junction 26 with the inner ends of the braces 13 and 14. Proportioned diagonal braces 27 and 28 have their outer ends connected together to the legs 5 in the panels below the girt 9 at the rotary front of the derrick and have their inner ends connected at spaced points to the elements 23 and 24. Odd diagonal braces 29 in the lowermost panel connect with the elements 23 and 24 at the lower ends of the braces 28 and at their opposite ends with the legs 5, all as shown in Figure 2 of the drawings.

On the ladder or forge sides of the derrick such as shown in Figure 3 of the drawings, the panel bounded by the girts 6 and 7 is different from the other panels by reason of the diagonal braces 30, 31 and 32, 33, respectively, which have their inner and upper ends connected to the plate 16. The outer and lower ends of the braces 30 and 32 are connected to the legs 5 while the outer and lower ends of the braces 31 and 33 are connected to the girt 6 at points spaced inwardly from the outer ends thereof, at plates 34 and 35, to which the upper ends of elements 36 and 37 are also connected. The lower ends of the elements 36 and 37 are connected to the lower ends of the legs 5. A perpendicular brace 38 is connected between the middle of the girt 6 and the plate 16. Abbreviated diagonal braces extend between the elements 36 and 37 and the adjacent legs 5.

The construction described provides full conformity to American Petroleum Institute specifications for the height, base, water table opening, gin pole capacity and height, window openings for rotaries, clear opening for drawworks, bull wheel girt clearance.

Although I have shown and described herein structural details and arrangements of the preferred embodiment of my invention, it is to be understood that I do not wish to limit the application of my invention thereto, except as may be required by the scope of the subjoined claims.

The words "midway point" and "points midway" as used herein are intended to generally allocate the points involved, except in these instances wherein exact location thereof is implicit, as slight variation away from the center or middle of the parts involved is embraced within the scope of the invention.

Having described the invention, what is claimed as new is:

10. An oil well derrick or the like comprising stages each comprising four leg sections, vertically spaced girts secured to and between adjacent leg sections, diagonal braces extending between and connected to points on the girts intermediate the ends of the girts and to points on the leg sections intermediate the adjacent girts, two of the diagonally opposed leg sections extending above the upper girt and two of the diagonally opposed leg sections extending below the lower girt.
15. 2. An oil well derrick or the like comprising four sectional corner legs, said legs comprising bottom sections of substantially the same length, intermediate sections consisting of a first section having diagonally opposed full lengths and diagonally opposed half-lengths, with the full lengths projecting upwardly above the half lengths, and the intermediate sections above said first section having diagonally opposed full lengths forming pairs with the legs of one pair in staggered relation vertically to the legs of the other pair to connect with the corresponding lengths of the first section and of upwardly succeeding sections, and a top section having diagonally opposed half lengths and diagonally opposed full lengths to cooperate with the lengths on the uppermost intermediate section, and joint means connecting the related terminals of the lengths in end to end relation.
20. 3. An oil derrick or the like in accordance with claim 2 wherein said lengths comprise angle-iron forms and said joint means comprises inner and outer angle-iron plates fitting the inner and outer sides of the terminals of the lengths, with bolts traversing the flanges of the forms and plates above and below the meeting point of the terminals.
25. 4. An oil derrick or the like in accordance with claim 2 wherein said lengths comprise angle-iron forms and said joint means comprises inner and outer angle-iron plates fitting the inner and outer sides of the terminals of the lengths, with bolts traversing the flanges of the forms and plates above and below the meeting point of the terminals, said derrick or the like further comprising angle iron girts having their vertical flange engaged with the outer side of the outer angle iron plate with at least one bolt traversing said vertical flange, a related flange of each of the angle iron plates and the related flange of the leg length positioned therebetween.
30. 5. An oil well derrick or the like comprising four sectional corner legs, said legs comprising bottom sections of substantially the same length, intermediate sections consisting of a first section having diagonally opposed full lengths and diagonally opposed half-lengths, with the full lengths projecting upwardly above the half lengths, and the intermediate sections above said section having diagonally opposed full lengths forming pairs with the legs of one pair in staggered relation vertically to the legs of the other pair to connect with the corresponding lengths of the first section and of upwardly succeeding sections, and a top section having diagonally

opposed half lengths and diagonally opposed full lengths to cooperate with the lengths on the uppermost intermediate section, and joint means connecting the related terminals of the lengths in end to end relation, and girts secured between the legs and to said joint means.

6. An oil well derrick or the like comprising four sectional corner legs, said legs comprising bottom sections of substantially the same length, intermediate sections consisting of a first section having diagonally opposed full lengths and diagonally opposed half-lengths, with the full lengths projecting upwardly above the half lengths, and the intermediate sections above said first section having diagonally opposed full lengths forming pairs with the legs of one pair in staggered

relation vertically to the legs of the other pair to connect with the corresponding lengths of the first section and of upwardly succeeding sections, and a top section having diagonally opposed half lengths and diagonally opposed full lengths to cooperate with the lengths on the uppermost intermediate section, and joint means connecting the related terminals of the lengths in end to end relation, and girts secured between the legs and to said joint means with diagonal braces extending between and secured at one end to adjacent girts at a point adjacent to the middle thereof and at their outer ends to the legs at a point substantially midway between the adjacent girts.

CHARLES L. FOX.
